CLAIM

The ornamental design for a shoe outsole, as shown and described.

DESCRIPTION

FIG. 1 is a front perspective view of a shoe outsole showing my new design;

FIG. 2 is a bottom view thereof;

FIG. 3 is a rear perspective view thereof; and,

FIG. 4 is a cross section taken through line 4-4 of FIG. 2. The broken lines showing the remainder of the shoe represent unclaimed subject matter and form no part of the claimed design.
